UNITED STATES PATENT OFFICE.

JOEL WALKER NEWTON, OF ELBERTON, GEORGIA.

CHURN.

SPECIFICATION forming part of Letters Patent No. 760,699, dated May 24, 1904.

Application filed January 5, 1904. Serial No. 187,811. (No model.)

To all whom it may concern:

Be it known that I, JOEL WALKER NEWTON, a citizen of the United States, residing at Elberton, in the county of Elbert and State of Georgia, have invented certain new and useful Improvements in Churns; and I do hereby declare the following to be a full, clear, and exact description of the invention, such as will enable others skilled in the art to which it appertains to make and use the same.

My invention relates to churns; and it consists of certain novel features of construction and combination of parts, as will be herein-after clearly set forth.

15 The prime object of my invention, among others, is to provide an operating mechanism for the churn-dasher and a closure for the churn-body which shall be reliably efficient in the performance of their respective offices.

20 Other objects and advantages will be hereinafter made clearly apparent, reference being had to the accompanying drawings, which are made a part of this application, and in which—

25 Figure 1 shows a perspective view of my invention complete ready for use. Fig. 2 is a longitudinal central section of my churn. Fig. 3 is a horizontal section of Fig. 2 on line 3 3. Fig. 4 is a perspective detail view of 30 the closure for my churn-body. Fig. 5 is a vertical section of Fig. 2 on line 5 5. Fig. 6 is a top plan view of the dasher as indicated by the section-line 6 6 in Fig. 2.

Referring to the numerals on the drawings, 35 1 designates a churn-housing, which may be made any desired size, said housing being provided with the closure or door-section 2 and with a vertical partition-wall 3, said partition-wall, combined with the outer wall of 40 the casing proper, being designed to afford suitable bearings for the driving-shaft 4.

In the housing thus or otherwise provided I locate the churn-body 5, which is formed with a flange around the lower edge or an extension of the bottom section, as indicated by 45 the numeral 6, said flange being adapted to be engaged by the clamps 7, which are bolted to the floor, so that the lip thereon will extend over the flange and reliably lock the 50 churn-body to the floor. The churn-body is

provided at its upper end with two diametrically-extending lugs or fingers 8, each of which is designed to fit in the bayonet-slot 9 provided in the flange of the auxiliary lid-section 10, whereby when said auxiliary lid-section 55 is dropped down over the upper end of the body-section the lug 8 will enter the bayonet-slots, when a partial rotation of said lid will prevent it from casually rising upward and hold it in a locked position until it is again 60 released by a rotary movement. Designed to fit bodily over the auxiliary lid-section 10 is the main lid or closure proper, 11, also having a bayonet-slot 12, similar to the slot 9, said bayonet-slot being formed in a depending 65 flange of sufficient size to reach downward to cover the flange upon the auxiliary lid 10. It therefore follows that by a partial rotation of the main closure 11 in an opposite direction from that imparted to the auxiliary closure 10 the bayonet-slot 12 will engage the protruding end of the lug 8 and securely hold both closures in a locked position. Each of the closures 10 and 11 is provided with a central aperture 13, adapted to receive the reciprocating dasher 14, the upper end of which is connected to the cross-head 15, the ends of which are provided with the guiding members 16, which fit into the ways 17, thereby permitting the members 16 to reciprocate 80 within said grooves incident to the reciprocation of the dasher 14.

The cross-head 15 is provided with the extension 18, which is pivotally connected by means of the link-section 19 to the crank 20, 85 said crank or wrist-pin 20 being carried by the wheel 21, mounted upon the shaft 22, the outer end of said shaft having keyed thereon the balance-wheel 23, designed to preserve the requisite momentum.

The shaft 22 is mounted in suitable bearings in the partition-wall 3 and the wall of the housing 1, as will be clearly seen by reference to Fig. 2, and keyed to said shaft between said walls is the gear-wheel 24, which 95 meshes with the idler-gear 25, also mounted in suitable bearings between said walls. The idler-gear meshes with the driving-gear 26 upon the shaft 4, and it therefore follows that by turning the shaft 4 by means of the crank 100

27 said train of gear-wheels will be actuated, causing the wheel 21 to be rapidly rotated and incidentally producing a reciprocatory movement upon the dasher 14 and causing the dasher-blades 28 to be moved upward and downward within the milk to be churned. The actuation of the dasher proper, 28, is therefore effected at the expense of a minimum amount of labor, and as the closure-sections 10 and 11 are securely locked against casual removal the milk will be confined within the receptacle or body portion 5 until butter is produced.

15 In addition to the anchoring-clamps 7 for holding the body of the churn in position I also provide suitably-apertured ears or staples 29, which are designed to be engaged by the hooks 30, secured to a contiguous part of the casing, and it is therefore obvious that the 20 churn-body, and more especially the closure-sections 10 and 11, will be held reliably in a locked position.

25 In order to aid in lifting the dasher-shaft and dasher attached to the lower end thereof, I provide the lifting-spring 31, the lower end of which is connected with the cross-head 15, while the upper end thereof is attached to the upper end of the housing, the tension of the 30 spring being directed to pull upward upon said cross-head, thus enabling the weight of the cross-head and parts carried thereby to be easily raised.

The parts of my churn may be cheaply man-

ufactured and readily assembled each in its respective operative position, and having described the preferred combination and construction of parts I wish to comprehend such substantial equivalents and substitutes as may be considered as falling fairly within the scope of my invention.

40 Having thus fully described my invention, what I claim as new, and desire to secure by Letters Patent, is—

The herein-described churn and churn-closure comprising a suitable housing; a churn-body 45 5 located within said housing; a flange formed upon the lower end of the churn; anchoring members 7 engaging said flange and secured to the floor; a dasher and dasher-shaft and means to reciprocate the same within the 50 churn-body and a closure therefor, comprising the auxiliary and main closures 10 and 11 respectively, each having depending flanges and slotted recesses formed in the flanges adapted to engage a lug or finger upon each 55 side of the upper end of the churn-body and additional means to hold the said closures against casual rotation, all substantially as specified and for the purpose set forth.

In testimony whereof I have signed my name 60 to this specification in the presence of two subscribing witnesses.

JOEL WALKER NEWTON.
